RECORD HOLDER FILE

Jack E. Schenker, Chicago, Ill.

Application January 16, 1942, Serial No. 426,981

11 Claims. (Cl. 129—15)

My invention relates to a file or album for containing phonograph records or the like which resembles a book when closed and an expandable file when opened, which file will simultaneously display a plurality of records, so that an individual selection can be made without the turning of pages or confusing searching for a particular record.

The invention has among its objects the production of a simple, desirable, efficient, inexpensive, practical and convenient device of the kind described that will afford most satisfactory protection to the contained records.

More particularly the invention has among its objects the production of an attractive file of the kind described, in appearance resembling a book consisting of two covers hingedly connected together by a back portion and containing a plurality of individual but associated pockets or envelope units suitably secured together, the associated pockets being secured as a complete unit to the inside face of each of the covers. The pockets are so constructed that they may be opened up or expanded to permit the ready removal or the insertion of any one of a number of records, or to be closed and embrace the records and securely retain the same in place when the covers are closed and the book or file set up or carried or otherwise handled.

The invention has among its further objects the production of a device of the kind described in which the pockets are provided with cover-like members and are automatically expanded and opened or closed upon grasping and opening or closing the covers of the file.

Another object is the production of a device in which the covers may be opened out flat on a desk, table or other support, and all of the records and information with regard thereto displayed at one time without requiring the successive turning over of separate pages to separately display individual records for selection.

A further object is the construction of a file of the kind described, in which the records are all well protected against injury and in which the records are kept clean when the file covers are closed. Phonograph records being ordinarily comparatively fragile or at least breakable, the matter of protection is very important, and since the records are not as efficient when they accumulate dust on the faces, the matter of keeping them clean or dustless is also of great importance.

Many other objects and advantages of the construction herein shown and described will be ob-

vious to those skilled in the art from the disclosure herein given.

To this end my invention consists in the novel construction, arrangement and combination of parts herein shown and described, and more particularly pointed out in the claims.

In the drawings wherein like reference characters indicate like or corresponding parts:

Fig. 1 is a perspective view of one form of my improved file with the covers closed;

Fig. 2 is an end elevation of the same with the covers opened to display a plurality of records in a manner that individual records may be readily selected;

Fig. 3 is a side elevation of a single pocket or file compartment;

Fig. 4 is an end elevation of the same;

Fig. 5 is a sectional view of the same taken substantially on line 5—5 of Fig. 3;

Fig. 6 is a top elevation of a portion of the pocket shown in Fig. 3 and sectional view taken on line 6—6 of the same figure, the top portion being omitted;

Fig. 7 is a view of an individual pocket or envelope blank illustrating one embodiment of the invention prior to folding and securing of the ends and securing adjacent pockets together to make up the assembly;

Fig. 8 is a perspective view of a portion of the invention or pocket in open position as illustrated in Fig. 2;

Fig. 9 is a view similar to Fig. 2 of a portion of a book embodying a modification;

Fig. 10 is a sectional view similar to Fig. 5 of the book illustrated in Fig. 9;

Fig. 11 is a plan view of a blank for constructing the modification illustrated in Figs. 9 and 10; and

Fig. 12 is a plan view of the cover blank illustrated in Fig. 11.

Referring now to the drawings, the file is made up of a plurality of individual pockets or envelopes indicated generally by the numeral 1, which are arranged between covers 2—2 hingedly connected together by means of a back 3, the pockets being suitably secured to the inner face of each of the covers 2, which are made substantially stiff or rigid, with the several pockets secured together to form a unit.

In the embodiment shown in Figs. 3 to 8 inclusive, each individual pocket unit is made up from a blank indicated generally by the reference B, and consists of the two sides 4—4 and an intermediate or cover portion noted generally as 5.

The intermediate portion, which in the construc-

tion shown is the top or outer edge of the pocket when assembled, is divided into two portions 6—6 by the scoring line 7. There is also provided the scoring lines 8, which permit the sides 4 to be turned or bent back, as shown particularly in Figs. 4 and 5.

Each end of the blank is preferably cut in or slitted as indicated at 9 and suitably scored as indicated at 10 and 11 to provide the wing portions 12 and 13. There is, likewise provided, a slot or slit 14 between the portions 6—6 which is enlarged between the ends as indicated at 15. As shown in Fig. 7, portions 16—16 are formed by slitting of the blank as indicated at 9, these serving to stiffen the central portion 5 between the two sides when the blank is folded into the completed pocket and provide a top finish as well as to permit increased length of the pocket while at the same time conserving material.

In setting up the particular pocket or compartment shown in Figs. 3 to 8 of the drawings, which is only one possible embodiment of the invention, the portions 4—4 are folded on the scoring lines 8 and along the scoring lines 7, 10 and 11. The flaps or portions 13 are brought together and glued or otherwise permanently attached to each other as is shown in Fig. 6.

The several pockets are secured together by gluing the outer faces of the pockets to adjacent pockets, as for example as indicated at 17 at the points stippled in Fig. 3, and the two outer pockets of the assembly are secured directly to the inner faces of the covers by gluing or in an equivalent manner.

When the covers are closed as shown in Fig. 1, the pockets are compactly folded together, and when the covers are opened, as for example flat, as shown in Fig. 2, the pockets are opened up or expanded. When the file is opened up as illustrated in Figs. 2 and 8, phonograph records indicated at 18 may be inserted through the slit or slot 14, or as readily withdrawn from the pocket. While ordinarily, only one record is placed in a pocket, of course, where the pockets are made large enough by properly proportioning the parts, two records may be inserted, but ordinarily this is not desirable. Each of the pockets may be provided with a suitable space designated 19, for the insertion of material indicating the particular content of the pocket, as for example, the name of the record or the composer or such other material as desired.

It will be noted that when the file is open, as shown in Fig. 2, the records 18 are disclosed and project from the pocket from which they may be readily picked out. When, however, the file is closed, and the pockets contracted, the record is almost entirely confined or enclosed, and as a result, is fully protected. The cut out portion 15 permits the ready grasping of the edge of the record when confined in the closed pocket.

Illustrated in Figs. 9 and 10 is a modified form of construction wherein the envelopes or pockets proper are formed from one or more sheets of material, while the cover portion is formed from one or more other separate sheets. The modified form illustrated embodies a back 3' and a plurality of side walls 4' joined together at the fold lines 21 and 22, a narrow bottom portion 23 being formed between each pair of fold lines 22. The blank illustrated in Fig. 11 is folded in opposite directions on the fold lines 21 and 22 respectively, to bring adjacent side walls 4' back to back as clearly illustrated in Fig. 10 and adjacent walls secured to one another along their side edges by

gluing or the like. The wing portions 12' and 13' are folded in the same manner as the corresponding portions 12 and 13 of the construction illustrated in Figs. 3 to 7 with the adjacent portions 13' being brought together and glued or otherwise attached to each other thereby forming a pocket similar to that previously described with the exception of the central or cover portions 5. Also preferably formed from the blank 10 are a plurality of flaps 24 positioned adjacent the fold lines 21, the flaps 24 being adapted to extend above the pockets as clearly illustrated in Figs. 9 and 10. As in the case of the previous construction the side walls 4' of the two outermost envelopes are glued or otherwise secured to the inner face of the cover members 2'. Cooperating with the pockets so formed is a cover member 5', the latter being provided with a plurality of slots 15 14 and having cover portions 6' corresponding to the portions 6 of the previous construction. As illustrated in Figs. 9 and 10 the cover member 5' is folded in opposite directions on the fold lines 7' and 8', the folded member assuming substantially the shape illustrated in Figs. 9 and 10. The cover member 5' is attached to the respective pockets by means of the flaps 24 which are secured to the lower face of the adjacent portions 6' thereby forming a completed structure similar in general appearance to that illustrated in Figs. 3 to 8 with the exception of the absence of the portions 16. As in the case of the latter construction detailed information of the various records may be placed upon the cover 5'.

While bottom portions 23 are illustrated between each pair of fold lines 22, if desired, a single fold line may be employed. Obviously, as I have shown in Fig. 11, the pockets or envelopes being formed from a single sheet of material, if desired, the modified construction may be produced by utilizing a plurality of individual or multiple blanks without departing from the spirit of my invention, the same being also true of the cover member 5'. The general operation of the construction shown in Figs. 9 to 12 inclusive is similar to that of the construction previously described and obviously in either case the device may be made in various sizes and contain any desired number of pockets.

It will be noted that in the construction illustrated the portions 6 and 6' form in effect a continuous cover portion for the pockets or envelopes, at the same time providing means for spreading the pockets when the book is opened and containing information regarding the contents of the respective pockets.

Having thus described my invention, it is obvious that various immaterial modifications may be made in the same without departing from the spirit of my invention; hence, I do not wish to be understood as limiting myself to the exact form, construction, arrangement, and combination of parts herein shown and described or uses mentioned.

What I claim as new and desire to secure by Letters Patent is:

1. An envelope of the kind described comprising a pair of side walls secured together adjacent opposite side edges and a cover portion secured to the upper edges of said side walls, said portion having an object receiving slit therein, and a longitudinally extending fold line upon which the cover portion may be folded back upon itself and brought substantially into the planes of said side walls.
2. An envelope of the kind described compris-

ing a pair of side walls secured together adjacent opposite side edges, fold lines adjacent the edges of said side walls each spaced from the junctures of said side walls and extending in substantially the same direction as said side edges, said respective fold lines at each edge of the side walls defining end portions between said fold lines and the adjacent juncture, and a cover portion secured to the upper edges of said side walls intermediate said end portions, said cover portion having an object receiving slit therein, and a longitudinally extending fold line on the cover portion whereby the latter may be folded back upon itself and brought substantially into the planes of said side walls.

3. An envelope of the kind described comprising a pair of side walls secured together adjacent opposite side edges, said side walls each having fold lines located adjacent the side edges and spaced from the junctures of said side walls and extending in substantially the same direction as said side edges, said respective fold lines at each edge of the side walls defining cooperative end portions between said side walls, flaps extending from the upper edges of the respective side walls intermediate said fold lines, and a cover portion secured to said flaps, said cover portion having an object receiving slit therein, and a longitudinally extending fold line on said cover portion whereby the latter may be folded back upon itself and brought substantially into the planes of said side walls.

4. In a device of the kind described the combination of a pair of connected covers, a plurality of envelopes positioned between said covers, each envelope comprising a pair of side walls secured together at their adjacent side edges, said side walls having fold lines therein adjacent the junctures of said walls to define end portions therebetween, and a cover portion secured to each of said envelopes, the cover portion having an object receiving slit therein, and a longitudinally extending fold line, each cover portion being foldable back upon itself to position the same substantially in the planes of the adjoining side walls when said covers are in a closed position.

5. In a device of the kind described the combination of a pair of connected cover members, a plurality of envelopes positioned between said members, each envelope comprising a pair of side walls secured together at their adjacent side edges, said side walls having fold lines therein adjacent the junctures of said walls to define end portions therebetween, flaps extending from the respective side walls intermediate said fold lines, and a cover portion secured to said flaps, the cover portion having an object receiving slit therein, and a longitudinally extending fold line, each cover portion being foldable back upon itself to position the same substantially in the planes of said side walls when said cover members are in a closed position.

6. An envelope of the kind described comprising a sheet of suitable material folded back upon itself with adjoining side edges at opposite ends of said sheet fold having inwardly extending slits therein, the portions of said side edges intermediate said slits and the edges of said sheet opposite said sheet fold being secured to one another to form a pocket, and a fold line on each face of the pocket, intersecting the side edges thereof intermediate said sheet fold and respective slits, said pocket having an object re-

ceiving slit therein coincident with one of said fold lines.

7. An envelope of the kind described comprising a sheet of suitable material folded back upon itself with adjoining side edges at opposite ends of said sheet fold having inwardly extending slits therein, the portions of said side edges intermediate said slits and the edges of said sheet opposite said sheet fold being secured to one another to form a pocket, and a fold line on each face of the pocket, extending in the same direction as said sheet fold and intersecting the side edges of the sheet intermediate said sheet fold and respective slits to define a top portion between the respective pocket face fold lines, said top portion having an object receiving slit therein.

8. An envelope of the kind described comprising a sheet of suitable material folded back upon itself with adjoining side edges at opposite ends of said sheet fold having inwardly extending slits therein, the portions of said side edges intermediate said slits and the edges of said sheet opposite said sheet fold being secured to one another to form a pocket, a fold line on each face of the pocket extending in the same direction of said sheet fold and intersecting the side edges of said sheet intermediate said sheet fold and respective slits to define a top portion between the respective fold lines on said pocket faces, said top portion having an object receiving slit therein, and fold lines on said faces extending substantially in the same direction as and adjacent said side edges, each pair of the last mentioned fold lines defining end portions therebetween.

9. In a device of the kind described the combination of a pair of connected cover members, a plurality of envelopes positioned between said members, each envelope comprising a sheet of suitable material folded back upon itself with adjoining side edges at opposite ends of said fold having inwardly extending slits therein, the portions of said side edges intermediate said slits and the edges of said sheet opposite said fold being secured to one another to form a pocket, and a fold line on each face of the pocket, intersecting the side edges thereof intermediate said sheet fold and the respective slits, said pocket having an object receiving slit therein coincident with one of said fold lines, the adjoining faces of said envelopes being secured to one another and the faces of the end envelopes being secured to the respective covers.

10. In a device of the kind described the combination of a pair of connected cover members, a plurality of envelopes positioned between said members, each envelope comprising a sheet of suitable material folded back upon itself with adjoining side edges at opposite ends of said fold having inwardly extending slits therein, the portions of said side edges intermediate said slits and the edges of said sheet opposite said fold being secured to one another to form a pocket, and a fold line on each face of the pocket, extending in the same direction as said sheet fold and intersecting the side edges of said sheet intermediate said sheet fold and respective slits to define a top portion between the respective pocket face fold lines, said top portion having an object receiving slit therein, the adjoining faces of said envelopes being secured to one another and the faces of the end envelopes being secured to the respective covers.

11. In a device of the kind described the combination of a pair of connected cover members, a plurality of envelopes positioned between said

members, each envelope comprising a sheet of suitable material folded back upon itself with adjoining side edges at opposite ends of said fold having inwardly extending slits therein, the portions of said side edges intermediate said slits and the edges of said sheet opposite said fold being secured to one another to form a pocket, a fold line on each face of the pocket, extending in the same direction as said sheet fold and intersecting the side edges of said sheet intermediate said sheet fold and respective slits to define a

top portion between the respective pocket face fold lines, said top portion having an object receiving slit therein, and fold lines on said faces extending substantially in the same direction as and adjacent said side edges, each pair of the last mentioned fold lines defining end portions therebetween, the adjoining faces of said envelopes bounded by said fold lines being secured to one another and the corresponding faces of the end envelopes being secured to the respective covers.

JACK E. SCHENKER.
